UNITED STATES PATENT OFFICE.

EMIL JACOBSEN, OF CHICAGO, ILLINOIS, ASSIGNOR TO AUTOMATIC ELECTRIC COMPANY, OF CHICAGO, ILLINOIS, A CORPORATION OF ILLINOIS.

AUTOMATIC TELEPHONE SYSTEM.

Application filed June 11, 1917, Serial No. 174,013. Renewed June 22, 1925.

To all whom it may concern:

Be it known that I, EMIL JACOBSEN, a citizen of the United States of America, and resident of Chicago, Cook County, Illinois, have invented certain new and useful Improvements in Automatic Telephone Systems, of which the following is a specification.

My invention relates in general to automatic telephone systems, and more particularly to those automatic systems which are commonly known as "two wire" systems, in which automatic switches at the exchange are controllable over the two sides of a calling line in series. Certain features of the invention, however, will no doubt be found to be of utility in systems of other type.

More specifically, my invention has for its principal object the provision of an improved connector switch having automatic trunk selecting functions, a connector of this type being well adapted for connecting with trunk lines extending to a private branch exchange; and being commonly known as a rotary connector. One of the details of improvement consists in the omission of the usual side switch, the circuit changes which were formerly performed by this mechanism being in my improved switch performed entirely by relays. In addition to the foregoing and other circuit improvements having to do with the operation of the connector switch, my invention is also concerned with supervisory circuits, some of which are provided to enable an attendant at the main exchange to supervise the operation of the connector switches, while others are for the purpose of operating signals before a private branch exchange operator.

All the foregoing improvements, together with others not now specifically mentioned, will be fully explained hereinafter, reference being had to the accompanying drawings.

The drawings comprising Figs. 1 and 2, when arranged in order with the corresponding lines at the ends thereof in alignment, show diagrammatically a complete circuit connection between a calling substation A in the main exchange and the called

substation A' in a branch exchange subsidiary thereto. This connection has been established through the medium of the individual line switch C, the first selector E, the second selector F, the rotary connector H, the trunk line 200—201 extending from the main exchange to the branch exchange and terminating at the latter point in the jack J, the operator's cord circuit O, and the multiple jack J'.

Referring to Fig. 1, the substation A may be of any approved automatic type, such for example as the substation shown in the British patent to Martin #1419 of 1910. As represented herein it comprises essentially the receiver 2, transmitter 3, switch hook 4, ringer 5, and condenser 6. Being an automatic substation there is also provided a pair of impulse springs 7 and 8 which may be controlled by an impulse wheel 9 through the medium of a finger hole dial (not shown).

The line conductors 11 and 12 of the substation A extend to the main exchange where they terminate in the individual line switch C. The line switch C is of the general type of line switch shown in the British patent to James #26,301 of 1906; being, however, of the particular type shown in U. S. Letters Patent #1,078,690, granted January 17, 1912, to Frank Newforth. Through the medium of the line switch C, the line of substation A when calling is given access to a plurality of trunk lines extending to selector switches.

The line switch C and a plurality of similar line switches are controlled in their trunk selecting operations by means of a master switch D. This master switch is of the general type of master switch disclosed in the above mentioned British patent to James #26,301 of 1906; being, however, more nearly of the particular type disclosed in the British patent to Martin #1419 of 1910, also previously referred to. As is well known, the function of the master switch is to maintain the plungers of all the idle line switches which it controls in position before the terminals of an idle trunk line.

One of the trunk lines to which the line switch C has access is shown extending to

the first selector E. The selector E may be of the general type of selector switch disclosed in U. S. Letters Patent No. 815,321, granted March 31, 1906 to Keith, Erickson & Erickson. The side switch and the private magnet are omitted, however, and the circuits are modified in accordance with the two wire system of control.

The second selector F is in all respects 10 similar to the first selector E.

The connector H may be of the general type of connector switch disclosed in U. S. Letters Patent No. 815,176, granted March 13, 1906, to Keith, Erickson and Erickson.

15 As before mentioned, however, the side switch and private magnet of the connector switch are omitted and the circuits are modified in accordance with the two wire system of control and also in order to ac-

20 complish the objects of my invention as will be explained fully hereafter. The wiper construction of connector H, the wiring of its bank contacts, and the grouping of the trunk lines terminating therein is similar to

25 the arrangement shown and described in the U. S. Letters Patent No. 1,312,558, granted August 12, 1919, to Talbot G. Martin. It may be stated that each bank level comprises ten contact sets in which terminate ten

30 trunk lines, which latter may be divided into any convenient number of groups. There may likewise be any desired number of trunk lines, from one to ten, in each group. Each contact set comprises four

35 contacts, which are the usual line, private or test contacts, and an extra test contact. This extra test contact is dead except in the case of the contact sets which are associated with the last trunk lines of the different groups, the two test contacts associated with the last trunk line of each group being connected together. The connector H is provided with the usual line and private

40 wipers and in addition with a fourth wiper 45 which is adapted to cooperate with the extra test contacts above mentioned.

One of the trunk lines accessible to the connector H is the trunk line 200-201, which is assumed to be the last trunk line, 50 in some particular group. The line conductors 200 and 201 terminate in the line contacts 195 and 198. The contact 197 is the regular test contact, while the contact 196 is the extra test contact. Since as al-

55 ready stated, the trunk line shown is assumed to be the last trunk line in the group, the contacts 196 and 197 are connected together. The trunk line shown is a two-way trunk line, that is, it is adapted to handle calls either to or from the private branch exchange. The latter class of connections are 60 taken care of by the individual line switch C' which is in all respects similar to the line switch C already described. At the

65 private branch exchange the trunk line

200-201 terminates in the jack J and is also provided with a line signal lamp L², the relays 202, 203 and 204, and the calling device key K. This apparatus is indicated collectively by the reference character M 70 and the operation of the various relays will be fully described hereafter. The operator's cord circuit O comprises the usual answering and calling plugs connected by condensers, the supervisory lamps L³ and L⁴ which 75 are controlled, respectively, by the relays 220 and 221, the ringing key K², and the combined listening and ringing key K'. This cord circuit may be used either for connecting two of the branch exchange sub- 80 stations such as the substation A', Fig. 1; or for connecting one of these branch sub- stations with the trunk line extending to the main exchange.

While I have shown throughout the drawings a plurality of batteries it is to be understood that there is preferably but one battery having its positive pole grounded, or rather there may be two batteries, one in the main exchange and the other in the 90 branch. In order not to encumber the drawings separate reference characters have not been applied to the different batteries and it will be understood that when a circuit is traced "to battery" it extends to the live or 95 ungrounded pole of the central or common battery. Associated with connector H, I have shown a ringing equipment R and a busy signalling machine Q. This apparatus may be of the usual type such as is found in 100 well known telephone systems. There are also shown two supervisory signal lamps L and L' which are preferably common to the group of connectors of which the connector H is one. The operation and function of 105 these lamps will be described later.

Having briefly described the apparatus involved, I will now proceed to explain more in detail the operation of the same. For this purpose it will be assumed that the subscriber at substation A desires to obtain 110 connection with the subscriber at substation A', this being the circuit connection shown in the drawing. When the receiver is removed at substation A to initiate the 115 call an energizing circuit is completed over the line conductors 11 and 12 for the line relay 14 of the line switch C. Upon attracting its armature the line relay 14 closes a circuit for the pull-in winding 18. Upon

120 energizing, the pull-in winding operates both the plunger arm 15 and the cut-off armature 16; the former through the medium of its plunger (not shown) forcing the bank springs 30 to 33, inclusive, into engagement, 125 respectively, with contacts 34 to 37, inclusive; and the latter disconnecting the line conductors 11 and 12, respectively, from ground and from the line relay 14. By the engagement of bank springs 30 and 33 with 130

contacts 34 and 37, respectively, the line conductors 11 and 12 are extended through normally closed contacts of the switching relay 57 to the double wound line relay 50 of the selector E. The line relay 50 is accordingly energized over the loop circuit including the substation A, and upon attracting its armature closes the usual energizing circuit for the slow acting release relay 51. Upon energizing in turn, the release relay closes a holding circuit for the line switch C which may be traced as follows: ground at G', working contact of armature 60 and the said armature, conductor 61, contact 35, spring 31, and the holding winding 17 to battery. Since the line relay 14 is slow acting it retains its armature attracted in order to maintain the pull-in winding 18 energized until after the above holding circuit is completed. A branch of the holding circuit extends by way of conductor 20 multiple test contacts in the banks of connector switches having access to the line of substation A, where by a ground potential on these test contacts the said line is made busy. By the engagement of bank spring 32 with contact 36 the master switch D is operated in the usual and well known manner to advance the plungers of all the remaining idle line switches into position before the next idle trunk line.

The foregoing operations have occurred in response to the removal of the receiver at substation A. The calling subscriber may now operate his calling device in accordance with the first digit of the desired number, thereby producing a series of interruptions in the circuit of the line relay 50 of the selector E. The line relay 50 is accordingly deenergized a number of times and at each deenergization transmits an impulse from ground G² through the slow acting relay 52 and the vertical magnet 55 in series to battery. In response to these impulses the vertical magnet operates to raise the switch shaft step by step until the wipers 70, 71 and 72 arrive at the horizontal level of bank contacts corresponding to the first digit of the called number. The slow acting relay 52 is energized in series with the vertical magnet and retains its armature attracted during the series of impulses. Upon the first upward movement of the shaft, the off normal springs 59 are closed, thereby completing an initial energizing circuit for relay 53 which extends as follows: ground at G', working contacts of armature 60, the armature of relay 52 and its working contact, off normal springs 59, and the winding of the said relay 53 to battery. Upon energizing, relay 53 locks itself independent of relay 52 at its upper armature, and at its lower armature prepares a circuit for the rotary magnet 54, which, however, is held open during the vertical movement of the

switch by the relay 52. At this point it should be mentioned that by the closure of the off normal springs 59 the switching relay 57 and the relay 53 were connected in series. But since the junction of these two relays has already been grounded, as explained, the relay 57 is short circuited and remains inoperative for the present.

When the slow acting relay 52 deenergizes at the end of the series of impulses it completes at its back contact the circuit of the rotary magnet 54. Upon energizing, the rotary magnet operates to rotate the wipers 70, 71, and 72 into engagement with the first set of contacts in the horizontal level opposite which they were raised. Near the end of its stroke the rotary magnet opens the circuit connecting relays 57 and 53 at its lower interrupter contact and at its upper interrupter contact opens the locking circuit of the last mentioned relay 53. Upon deenergizing, relay 53 breaks a circuit of the rotary magnet 54, which accordingly retracts its armature to again close its interrupter contacts. The operation now depends upon whether the trunk line the terminals of which are now engaged by the switch wipers is busy or not. If this trunk line is busy the test terminal with which the test or private wiper 71 is in engagement will have ground potential upon it, which ground potential will serve to maintain the switching relay 57 short circuited and to again energize relay 53. The rotary magnet circuit is therefore again completed and the same cycle of operations is repeated, whereby the switch wipers are advanced into engagement with the next set of bank contacts. It will be seen then that the relay 53 will operate as an interrupter or stepping relay to advance the switch wipers step by step through the medium of the rotary magnet as long as the test wiper 71 continues to engage busy or grounded test contacts. When an idle trunk line is reached, however, the test wiper 71 will find no ground potential upon the associated test contact, from which it follows that the stepping relay 53 cannot again energize, thus bringing about the cessation of the rotation. In addition, since the relay 57 is no longer short circuited, it at once energizes in series with the relay 53. Relay 57 is of sufficiently high resistance to prevent the operation of relay 53. Upon energizing, relay 57 opens at its lower armature a contact in the circuit of the release magnet 56 to guard against the release of the switch upon the deenergization of relays 50 and 51; shifts at its upper armature the private wiper 71 from its upper to its lower terminal; and at its two inner armatures disconnects the incoming line conductors from the windings of the line relay 50 and extends them instead by way of wipers 70 and 72, bank

contacts 73 and 75 and normally closed contacts of switching relay 87 to the double wound line relay 85 of the second selector F.

- 5 Immediately following the extension of the calling line as above described the line relay 85 is energized over the two sides of the calling line in series and upon attracting its armature closes the usual energizing 10 circuit for the slow acting release relay 86. Upon attracting its armature relay 86 completes a holding circuit extending back to the selector E and line switch C over the following path: ground at G⁴, working contact of armature 88 and the said armature, conductor 89, bank contact 74, wiper 71, and the upper armature of relay 57 and its working contact to junction point 65; where the circuit divides, one branch extending by 15 way of the winding 57 and the winding of relay 53 to battery, while the other branch extends over a previously traced path through the holding winding 17 of line switch C to battery. It is to be understood 20 that the above described holding circuit is completed before the slow acting release relay 51 of selector E has had time to de-energize.

The calling subscriber may now operate 30 his calling device in accordance with the second digit of the called number, thereby producing a series of interruptions in the circuit of the line relay 85 of the selector F. The selector F is now operated in precisely 35 the same manner that selector E was operated, to select in accordance with the digit called the required group of connector switches and to thereafter automatically select a trunk line extending to an idle connector in the selected group. Since these 40 operations have already been described in the case of selector E it will be unnecessary to repeat the explanation. It will be sufficient to say that when the wipers 90, 91 and 92 of the selector F arrive at the set 45 of bank contacts in which the selected idle trunk line terminates, assumed to be the bank contacts 93, 94 and 95, the rotation is stopped and the switching relay 87 is energized in the usual manner to extend the line 50 conductors by way of wipers 90 and 92, bank contacts 93 and 95, and normally closed contacts of the answering bridge relay 110 to the double wound line relay 100 of the 55 connector H.

The line relay 100 is accordingly energized over the calling subscriber's loop and upon attracting its armature closes the circuit of the slow acting release relay 101. 60 Upon energizing in turn, the relay 101 completes a holding circuit for the selector F and the other switches which may be traced as follows: ground at G⁴, working contact of armature 114 and the said armature, conductor 160, bank contact 94, wiper 91, and

the upper armature of relay 87 and its working contact to junction point 96; where the circuit divides, one branch extending by way of the winding of relay 87 and the winding of relay 97 to battery, and the other branch extending back to the selector E and the line switch C over a path previously traced.

The calling subscriber may now operate his calling device in accordance with the 70 third digit of the called number, thereby producing a series of interruptions in the circuit of the line relay 100 of the connector H. The line relay therefore is deenergized a number of times and at each deenergization 80 transmits an impulse through the slow acting relay 102 and the vertical magnet 112 as follows: ground at G⁷, armature 113 and its resting contact, armature 115 and its working contact, off normal springs 121 and 119, winding of the slow acting relay 102, and the winding of the vertical magnet 112 to battery. In response to these impulses 85 the vertical magnet operates to raise the switch shaft step by step until the wipers 191, 192, 193 and 194 arrive at the horizontal level of bank contacts in which are located contacts which constitute terminals of trunk lines extending to the desired private branch exchange. The slow acting relay 90 95 102 is energized in series with the vertical magnet and retains its armature 116 attracted during the series of impulses, thereby preventing the opening of the vertical magnet circuit by the shifting of the off normal springs, which operation occurs as soon as the shaft leaves its normal position.

The calling subscriber may now operate his calling device in accordance with the final digit in the called number, which digit 100 it should be mentioned, will correspond to the position of the contact set which is associated with the first trunk line of the desired group. For example, if the first trunk line of the group of trunk lines extending 105 to the wanted branch exchange terminates in the fourth contact set in the selected level, then the final digit to be called will be the digit 4. When the final digit is called a series of interruptions is again produced in 110 the circuit of the line relay 100. Now, however, the off normal springs 117 to 121, inclusive, being in the position shown in the drawing, and the slow acting relay 102 having deenergized, the line relay transmits a 115 series of impulses to the rotary magnet 109 over the following path: ground at G⁷, armature 113 and its resting contact, armature 115 and its working contact, off normal springs 121 and 120, armature 116 and its resting contact, resting contact of armature 132 and the said armature, armature 129 and its resting contact, armature 144 and its resting contact, and the winding of the rotary magnet 109 to battery. In response to 120

these impulses the rotary magnet 109 is operated to rotate the wipers 191 to 194, inclusive, into engagement with the contact set in which terminates the first trunk line of the selected group. It will be noted that a branch of the rotary magnet circuit extends from junction point 162 through the winding of relay 106 to battery. It follows that relay 106 will be energized in parallel with the rotary magnet and since this relay is slow acting it retains its armatures in operated position during the rotation of the switch. By the attraction of its armatures 133 and 134 the relay 106 holds open the circuits of the test relay 104 and the stepping relay 105, respectively, as will appear later, and at its armature 135 opens the circuit of the upper winding of the switching relay 108. In addition, at the working contact of the said armature 135, relay 106 closes a circuit for relay 107 as follows: ground at G^e, working contact of armature 114 and the said armature, conductor 160, armature 126 and its resting contact, armature 135 and its working contact, and the upper winding of relay 107 to battery. Upon energizing, relay 107 establishes a locking circuit for itself which may be traced as follows: ground at G^e, working contacts of armature 114, conductor 161, armature 141 and its resting contact, armature 139 and its working contact, and the upper winding of the said relay 107 to battery. As an additional result of its energization, relay 107 prepares a test circuit at its armature 136 which includes the test wiper 192 and the winding of the test relay 104. This circuit is held open, however, during the rotation of the switch by the relay 106 at its armature 133 and since moreover it can be of no effect except when all the trunk lines of the selected group are busy it may be neglected for the present. A further result of the energization of relay 107 is the preparation of a circuit for the stepping relay 105 at its armature 140. This circuit also is held open during the rotation of the switch at the armature 134 of relay 106. The operation of the line reversing armatures 137 and 138 at this time is of no particular consequence. At the end of the final series of impulses relay 106 deenergizes, thereby closing at its armatures 134 and 135, respectively, circuits for the stepping relay 105 and the upper winding of the switching relay 108. The operation now depends upon whether the first trunk line the contacts of which are now engaged by the wipers 191 to 194, inclusive, is busy or not. It has been stated before that the trunk line shown in the drawing is the last trunk line of the group to which it belongs and we will therefore assume in this explanation that the remaining trunk lines are busy. This being the case the test contact with which the private

or test wiper 193 is now in engagement will have a ground potential upon it. As a result of this ground potential the upper winding of relay 108 is short circuited, this relay being thereby prevented from energizing, and a circuit is completed for the stepping relay 105 as follows: grounded test contact, private wiper 193, resting contact of armature 134 and the said armature, resting contact of armature 163 and the 70 said armature, interrupter contact of the rotary magnet 109, working contact of armature 140 and the said armature, and the winding of relay 105 to battery. Upon energizing, relay 105 locks itself over the 75 following path: ground at G^e, working contacts of armature 114, conductor 161, armature 141 and its resting contact, working contact of armature 131 and the said armature, resting contact of armature 163 and the 80 said armature, interrupter contact of the rotary magnet 109, working contact of the armature 140 and the said armature, and the winding of said relay 105 to battery. At the same time relay 105 completes a new 85 energizing circuit for the rotary magnet 109 which may be traced as a branch of its locking circuit above described as follows: junction point 166, working contact of armature 132 and the said armature, 90 armature 129 and its resting contact, armature 144 and its resting contact, and the winding of the rotary magnet to battery. In response to the closure of its circuit the 95 rotary magnet is energized and the wipers 100 191 to 194, inclusive, are thereby advanced into engagement with the contact set associated with the next trunk line. It will be seen that when the rotary magnet is operated as above described the slow acting relay 106 is not energized in parallel therewith. Near the end of its stroke the rotary magnet opens its interrupter contact, thereby breaking the locking circuit of relay 105, which relay is accordingly deenergized 105 to in turn break the circuit of the rotary magnet. The rotary magnet therefore is deenergized and again closes its interrupter contact. Since it has been assumed that the 110 second trunk line also is busy, the test wiper 115 193 will find a ground potential on the test contact associated with that trunk line, resulting in the continued short circuiting of the switching relay 108 and the reenergization of the stepping relay 105. When relay 120 105 energizes again the entire cycle of operation just described is repeated, whereby the switch wipers are advanced another step. Thus it will be seen that as long as the private wiper 193 continues to engage grounded 125 or busy test contacts, the rotation of the switch will continue under the control of the stepping relay 105. Before explaining the operations which occur when an idle trunk line is reached it should be pointed 130

out that the upper winding of relay 108 is not only short circuited by ground upon busy test contacts but also, whenever the stepping relay 105 is energized, by ground from G^o over a branch of the previously described locking circuit of the said stepping relay. This branch includes the armature 131 of relay 105 and the armature 134 of relay 106.

- 10 We have assumed that the last trunk line of the group, being the one shown in the drawing, was idle when the call was made. It follows then that when the test wiper 193 arrives at test contact 197 it will find 15 no ground potential. An energizing circuit is therefore at once established, while relay 105 and the rotary magnet 109 are still energized, for the cut off winding 17' of the line switch C'. This circuit may be 20 traced as follows: ground at G^o , working contacts of armature 114, conductor 161, armature 141 and its resting contact, working contact of armature 131 and the said armature, armature 134 and its resting contact, 25 test wiper 193, test contact 197, and the holding winding 17' to battery. By the energization of the holding winding 17' the cut off armature 16' is operated, thereby disconnecting the trunk conductors 200 and 30 201 from their normal battery and ground connections in the line switch C'. As before mentioned the above circuit serves also to short circuit the upper winding of relay 108 in order to prevent its energization 35 when an idle contact set is reached until after the deenergization of the stepping relay 105. When this operation occurs the holding winding 17' is maintained energized for a brief interval over the following circuit: ground at G^o left hand working contact of armature 114 and the said armature, conductor 160, armature 126 and its resting contact, armature 135 and its resting contact, upper winding of relay 108, 40 test wiper 193, test contact 197, and the winding 17' to battery. The relay 108 is energized when the above circuit conditions are established, not only by reason of the current which flows through the winding 45 of the winding 17' of the line switch C', but also because of current flow in two branch circuits which extend from wipers 193 and 192, respectively, through the windings of relays 105 and 104. The circuit 50 through the former relay 105 has already been traced while that through the test relay 104 will be described in detail during the description of the operation of calling a busy line. It should be mentioned, however, 55 that the test relay 104 is of high resistance, is given a stiff adjustment, and because of the shunting effect of the lower resistance relay 105, does not energize. As to relay 105, although it energizes at the same time or an instant later than relay 108 does, its

circuit is immediately broken by the de-energization of relay 107 as will hereinafter appear. Returning to the relay 108, its energization has the following results: At armature 144 the circuit of the rotary magnet 70 109 (and also the circuit of the test relay 104) is opened. At the resting contact of armature 141 the locking circuit of relay 107 is broken, thereby permitting the deenergization of this relay. Upon deenergizing, relay 107 breaks the circuit of the test relay 104 at another point (armature 136) and at armature 140 opens the energizing circuit of the stepping relay 105. Returning now to the relay 108, by the complete attraction of its armature 141, this relay completes a new energizing circuit for the holding winding 17' which may be traced as follows: ground at G^o , working contacts of armature 114, conductor 161, armature 141 80 and its right hand working contact, test wiper 193, test contact 197, and the holding winding 17' to battery. A branch of the above circuit extends by way of the armature 141, its left hand working contact and the lower winding of the said relay 108 to battery, thereby serving to lock relay 108 in energized position.

A still further result of the energization of relay 108 is the closure of a signalling circuit extending over the trunk line to the branch exchange which may be traced as follows: ground at G^o , generator Gen, working contact of ringing interrupter R, resting contact of armature 124 and the said armature, armature 138 and its resting contact, armature 143 and its working contact, wiper 194, bank contact 198, conductor 201, condenser 205, resting contact of armature 206 and the said armature, right hand winding of ring down locking relay 203, condenser 206', conductor 200, bank contact 195, wiper 191, working contact of armature 142 and the said armature, resting contact of armature 137 and the said armature, armature 123 100 and its resting contact, upper winding of the ringing cut off relay 103 and the central battery to ground G^o . Ringing current from generator Gen is thus projected out over the trunk conductors 200 and 201 to operate the ring down relay 203 at the operator's position in the branch exchange. Upon attracting its armature, relay 203 completes a locking circuit for itself which includes the line lamp L^2 . By the illumination of the lamp L^2 the operator is advised that a call has been received. She will therefore select an idle cord circuit, assumed in this case to be the cord circuit O, and insert the answering plug 110 thereof in the jack J. By the insertion of the plug in the jack a circuit is completed in an obvious manner for the cut off relay 204. By the energization of the relay 204, the right hand winding of the ring down relay 203 is disconnected from in bridge of 115 120 125 130

- the trunk; the locking circuit of the said relay 203 is broken, whereby the lamp L^2 is extinguished; and in addition the polarized relay 202 is bridged across the trunk line to the right of condensers 205 and 206'. At the connector H by the operation of interrupter apparatus R the generator Gen is intermittently cut out of the ringing circuit and the booster battery substituted therefor.
- 10 The ring cut off relay 103 is so adjusted that it will operate on the current from generator Gen and the exchange battery in series when the direct current bridge through the polarized relay 202 is closed at the branch exchange, or on current from the exchange battery and the booster in series under the same condition; but it will not operate from generator current alone when the condensers associated with the trunk line at the branch exchange are included in the bridge thereat.
- 15 When the operator responds and the relay 202 is bridged across the trunk line the relay 103 is energized at once, irrespective of the position of the interrupter apparatus R, and locks itself over the following circuit: ground at G^6 , working contacts of armature 114, working contact of armature 122 and the said armature and the lower winding of relay 103 to battery. A branch of the above circuit
- 20 supplies ground to the lower winding of the back bridge or reversing relay 110. The lower winding of the relay 110 is connected as shown rather than to ground direct in order that the calling subscriber may detect
- 25 the operation of the ringing apparatus by the tone which he gets by induction between the windings of relay 103. To proceed, by attracting its armatures 123 and 124, relay 103 disconnects its upper winding and the
- 30 lead to the interrupter apparatus R and at the working contacts of these armatures finally completes the talking circuit through the connector H. The answering bridge relay 110 is now energized in series with the polarized relay 202 at the branch exchange, the circuit being traceable without difficulty over the heavy line conductors, and upon attracting its armatures 146 and 147 reverses the incoming line conductors as regards their
- 35 connections to the windings of the line relay 100. This causes a reversal of current in the calling line which may operate a meter (not shown) in the usual and well known manner. The attraction of armatures 148 and 149 of relay 110 is of no effect but the circuits controlled by these armatures will be described later.
- 40 At the branch exchange, the operator will now throw her listening key K' , and upon ascertaining of the calling subscriber the name of the party wanted at the branch exchange, she will complete the connection by inserting the calling plug of the cord circuit in use in the jack of the proper local
- 45 line, assumed to be the jack J' . She will

then operate her ringing key K^2 to signal the called subscriber. When the plug is inserted in the jack J' a circuit is completed for the supervisory lamp L^4 in the usual manner over the sleeve of the cord circuit. 70 As regards the supervisory lamp L^3 , this lamp is not now illuminated, for the direction of current flow through the windings of the polarized relay 202 is such that the armature of this relay is operated to open 75 the circuit of the said supervisory lamp L^3 .

When the local subscriber answers, his transmitter is supplied with talking current through the windings of relay 221 at the cord circuit. This relay is accordingly energized to break the circuit of the supervisory lamp L^4 , thus advising the operator that the called party has answered. The relay 220 serves no purpose in a connection of this character, being of utility only when 85 on local connections and remains deenergized.

The required connection has now been established. The transmitter at the calling substation is supplied with talking current 90 through the windings of the double wound relay 100 at the connector, while the transmitter at the called substation is supplied with talking current through the windings of the relay 221 at the cord circuit O as before mentioned. The path for voice currents is shown in heavy lines and needs no detail description.

When the conversation is over both subscribers will replace their receivers. When 100 the receiver is hung up at substation A' the relay 221 is deenergized, thereby again closing the circuit of the supervisory lamp L^4 to give the operator a disconnect signal. When the receiver is replaced at the substation A' the circuit of the line relay 100 is broken, whereby the line relay 100 deenergizes and closes the previously described energizing circuit for the slow acting relay 106, the rotary magnet not being operated 105 because the branch of this circuit which includes its winding is now open at the armature 144 of relay 108. Upon energizing, the relay 106 disconnects the conductors 160 from the upper winding of relay 108 at its 110 armature 135 and at the same time closes the energizing circuit of relay 107. Upon energizing, relay 107 reverses the line wipers 191 and 194 as regards their connections to the windings of the answering bridge relay 110, thereby reversing the direction of current flow over the trunk conductor 200-201. By this operation the polarized relay 202 at the branch exchange is operated to close the circuit of the supervisory lamp L^3 in an obvious manner. The operator is thus given a disconnect signal by both the calling and the called subscribers.

An instant after the energization of relay 106 the slow acting relay 101 deenergizes, 115

its circuit having been broken by the deenergization of the line relay 100. By the deenergization of the relay 101 the circuit of relay 106 is broken at armature 115 and at 5 armature 114 ground G^6 is disconnected from conductors 160 and 161. Since relay 110 is still energized, however, conductor 161 remains grounded for the present over an alternative path which may be traced as 10 follows: ground at G^{10} , working contact of armature 145 and the said armature, armature 125 and its working contact, and the armature 148 and its working contact to the conductor 161. Relays 103 and 108 whose locking circuits include the conductor 161 are thus prevented from deenergizing. When ground is disconnected from conductor 160 the holding circuit over which the switching relays 87 and 57 of the selectors 15 F and E, respectively, and the holding winding 17 of the line switch C have been energized is broken. Upon the deenergization of relays 87 and 57 the selectors F and E are restored to normal through the medium of their respective release magnets 84 and 56 in the usual and well understood manner. Upon the deenergization of the holding winding 17 the plunger of the line switch C is withdrawn from the bank, 20 whereupon all of the automatic switching apparatus involved in the connection with the exception of the connector H will have been restored to an idle condition in readiness for another call. An instant after ground G^6 is removed from conductor 160 to permit 25 the release of the selector switches and the line switch as above described, the slow acting relay 106 deenergizes and ground G^{10} is thereby connected to conductor 160 over the following path: ground G^{10} , working contact of armature 145 and the said armature, armature 125 and its working contact, armature 148 and its working contact, conductor 161, armature 141 and its right hand 30 working contact, upper winding of relay 108, resting contact of armature 135 and the said armature, resting contact of armature 126 and the said armature to conductor 160. The upper winding of relay 108 is of low 35 resistance, preferably about 100 ohms, and the test contact 94 and its multiples are therefore brought sufficiently near to ground potential to make the connector H busy. 40

As a further result of the deenergization 45 of the relay 101 a circuit is closed for the relay 164 over the following path: ground at G^7 , armature 113 and its resting contact, armature 115 and its resting contact, off normal springs 118 and 117, armature 149 50 and its working contact, lower winding of relay 107 and the winding of the relay 164 to battery. It will be noted that this circuit is completed before the deenergization 55 of the slow acting relay 106 occurs, from 60 which it will be seen that the relay 107 will

be maintained energized after its initial energizing circuit is broken. By the operation of relay 164 the lamp L' is lighted. The lamp L' is in the nature of an off normal signal and with relay 164 is preferably common to the group of connectors of which the connector H is one. When lighted it indicates to the switch board attendant that some connector in the group with which it is associated is off normal. 75

In response to the lighting of supervisory lamps L^4 and L^8 the operator at the branch exchange will now remove the cord circuit O from jacks J and J'. When the plug is removed from jack J the relay 204 deenergizes, whereupon the bridge across the trunk conductors, including the polarized relay 202, is broken. By the opening of this bridge at the branch exchange the answering bridge 110 at the connector H is deenergized with the following results: At armature 148 ground G^{10} is disconnected from conductor 161 to permit the deenergization of relays 103 and 108. At the working contact of armature 149 the circuit of relays 107 and 164 is broken, whereupon these relays deenergize also. Finally at the resting contact of armature 149 a circuit is completed for the release magnet 111 over the following path: ground at G^7 , armature 113 and 90 its resting contact, armature 115 and its resting contact, off normal springs 118 and 117, armature 149 and its resting contact, and the winding of release magnet 111 to battery. The connector H is then restored to 95 normal in the customary manner through the medium of the said release magnet. 100

In case the calling subscriber at substation A desires to obtain connection with another substation, and through accident or design, does not first hang up his receiver to release, but starts to operate his calling device again, the relays 106 and 107 are energized during each series of impulses. By the operation of the latter relay current in 105 the trunk conductors 200 and 201 is reversed to operate the polarized relay 202 as before explained. The supervisory lamp L^8 is thus illuminated intermittently for the purpose of recalling the operator before she takes down the connection. In case the operator at the branch should remove the plug from jack J before the subscriber at substation A hangs up his receiver the answering bridge relay 110 is deenergized and closes a circuit for the supervisory lamp L as follows: ground at G^{10} , working contact of armature 145 and the said armature, armature 125 and its working contact, armature 148 and its resting contact and the lamp L to battery. The lamp L is similar to the lamp L' , that is, it is an off normal signal common to the group of connectors and indicates that a complete connection through the automatic switch board has been left up owing to the failure 115 120 125 130

of the calling subscriber to replace his receiver.

It will now be assumed that all the trunk lines of the particular group in question, including the trunk line 200—201 as shown in the drawing, were busy at the time that the connector H was operated as previously described. Under these circumstances there will be a ground potential upon the test contact 197, and since the trunk line shown is the last trunk line of the group, upon the test contact 196 also. When the test wiper 192 therefore arrives at the test contact 196 a circuit will be completed for the test relay 104 as follows: grounded test contact 196, wiper 192, resting contact of armature 133 and the said armature, contact 127, spring 128, armature 136 and its working contact, winding of test relay 104, armature 144 and 10 its resting contact, and the winding of the rotary magnet 109 to battery. The test relay 104 is short circuited, however, until the stepping relay 105 deenergizes upon the last operation of the rotary magnet 109, and 15 does not energize therefore until the armature 132 separates from its working contact. The instant this occurs relay 104 energizes in series with the rotary magnet over the circuit just described. Owing to the high 20 resistance of relay 104 the rotary magnet 109 deenergizes and remains inoperative. Upon attracting its armature 126 relay 104 breaks its original energizing circuit and completes a locking circuit for itself as follows: ground at G^o, working contact of 25 armature 114 and the said armature, conductor 160, armature 126, spring 128, armature 136 and its working contact, winding of the said relay 104, armature 144 and its 30 resting contact, and the winding of the rotary magnet 109 to battery. As a further result of its energization relay 104 opens that portion of the rotary magnet circuit which extends back to the line relay 40 100, at its armature 129; at its armature 163 opens the circuit of the stepping relay 105; and at its armature 130 connects a lead from the busy signalling machine Q to the lower heavy talking conductor. By this 45 latter operation the calling subscriber is given a busy signal informing him that for the time being the called subscriber is inaccessible. He will therefore hang up his receiver and the automatic switches involved in the connection will be released 50 substantially as before described.

I wish it to be understood that the group of connectors of which the connector H is one may have access to individual subscribers' lines such as the line of substation A, as well as to private branch exchange trunk lines. The two test contacts, corresponding to test contacts 196 and 197, of each such individual line should be joined 55 together, of course; and when calling one

of these lines the connector employed will have no automatic trunk selecting movement.

Having described my invention what I consider to be new and desire to have protected by Letters Patent will be pointed out in the appended claims.

What I claim as my invention is:

1. In a telephone system, a temporarily established connection including in serial relation an automatic switch, a trunk line, and an operator's cord circuit, a signal at the operator's position, a calling device at the calling substation for controlling said switch, and means in said switch for controlling said signal whereby if said calling device is operated after the connection is established the said signal is actuated at each operation thereof. 75

2. In a telephone system, a temporarily established connection including in serial relation an automatic switch, a trunk line, and an operator's cord circuit, a signal at the operator's position, a calling device at the calling substation for controlling said switch, a relay responsive to the operation of said calling device after the connection is established for reversing the direction of current flow in said trunk line, and a device responsive to such reversal to actuate said 95 signal. 90

3. In a telephone system, subscribers' lines, means including a final connector switch for extending a connection from a calling line to a called line, mechanism for releasing said switch at the end of the conversation controlled over the line circuit which is opened last, and a signal automatically actuated if the called line circuit is 100 opened first. 105

4. In a telephone system, subscribers' lines, means including a final connector switch for extending a connection from a calling line to a called line, mechanism for releasing said switch at the end of the conversation controlled over the line circuit which is opened last, two signals associated with said switch, means for automatically actuating one of said signals if the calling line circuit is opened first, and means for automatically actuating the other of said signals if the called line circuit is opened first. 110 115

5. In a telephone system, a connector switch having directive relay controlled primary and secondary operating magnets, a plurality of switching devices, each having but two positions, having sole control of all the local circuits of said switch, a temporarily established connection between a calling and a called line including said switch, and mechanism for releasing said switch at the end of the conversation under the control of the line circuit which is last opened. 125

6. In a telephone system, a connector 130

switch having directive relay controlled primary and secondary operating magnets, a plurality of switching devices, each having but two positions, having sole control of all the local circuits of said switch, a temporarily established connection between a calling and a called line including said switch, and mechanism releasing said switch at the end of the conversation requiring the opening of both the calling and called line circuits to render it effective.

7. In a telephone system, a group of lines extending from an exchange to a distant point, other lines, an automatic switch having directly controlled primary and secondary movement for connecting a calling one of said other lines with the first one of said first lines, means in said switch operated if the first one of said line is busy for causing said switch to automatically select another one of said first lines, circuits for controlling the primary and secondary movements of said switch and for starting and stopping the idle line selection, and a plurality of circuit changing switching devices, each having but two positions, having sole control of said circuits.

8. In a telephone system, a group of lines extending from an exchange to a distant point, other lines, an automatic switch having directly controlled primary and secondary movement for connecting a calling one of said other lines with the first one of said first lines, means in said switch operated automatically for selecting another one of said first lines if the first one is busy, circuits for controlling the primary and secondary movements of said switch and for starting and stopping the idle line selection, a plurality of circuit changing switching devices, each having but two positions, having sole control of said circuits, and release mechanism requiring the opening of both the connected line circuits to render it effective.

9. In a telephone system, an automatic directly controllable switch having automatic trunk selecting functions, trunk lines accessible to said switch, test contacts for said lines and a cooperating test wiper in said switch, a line switching relay in said switch, a relay controlling the automatic trunk selection, parallel branch circuits extending from said test wiper through said relays, respectively, to the opposite poles of the central battery, said circuits being exclusive of any other wiper of said switch, and means for automatically closing said circuits at the end of the directly controlled movement of said switch.

10. In a telephone system, an automatic directly controllable switch having automatic trunk selecting functions, trunk lines accessible to said switch, test contacts for said lines and a cooperating test wiper in

said switch, a line switching relay in said switch, a relay controlling the automatic trunk selection, parallel branch circuits extending from said test wiper through said relays, respectively, to the opposite poles of the central battery, and a relay energized during the directly controlled movement of said switch and deenergized thereafter to close said circuits simultaneously.

11. In a telephone system, an automatic directly controllable switch and lines accessible thereto, test contacts for said lines and a cooperating test wiper in said switch, test and switching relays in said switch adapted respectively, to prevent and to complete connection to a called line, parallel branch circuits extending from said test wiper through said relays, respectively, to the opposite poles of the central battery, an operating magnet, and a slow acting relay energized in parallel therewith during the operation of said switch and deenergized thereafter to close said branch circuits.

12. In a telephone system, subscribers' lines, an automatic connector switch, means for operating said switch to connect with a desired called line, test and switching relays in said connector adapted, respectively, to prevent and to complete connection to a called line, an operating magnet for said switch, a slow acting relay energized in parallel therewith during the operation of said switch and deenergized thereafter to close a circuit through said relays in series, and a test wiper connected to the junction of said relays and cooperating with the test contact of the called line to cause the energization of either the said test relay or the said switching relay, depending on whether the called line is busy or idle.

13. In a telephone system, subscribers' lines, a final connector switch having access to said lines, a directly operable magnet for said switch for controlling said switch to extend a connection to a particular line, a test relay adapted to prevent connection with said called line if the same is busy, and a test circuit including the said relay and magnet in series, a means controlled by said relay for giving a busy signal to the calling subscriber.

14. In a telephone system, subscribers' lines, a final connector switch having access to said lines, a directly operable magnet for said switch for controlling said switch to extend a connection to a particular line, a test relay adapted to prevent connection with said called line if the same is busy, a test circuit including the said relay and magnet in series, means controlled by said relay for giving a busy signal to the calling subscriber, and an operating circuit for said magnet excluding the said relay and effective to short circuit the said relay when closed.

15. In a telephone system subscribers' lines, means including a final connector switch having a magnet operable for extending a connection from a calling to a called line, a test relay in said switch and means in said switch for operating said relay in series with said magnet when the called line is busy, to signal the calling subscriber and prevent the further operation of said magnet. 70
16. In a telephone system, subscribers' lines, a final connector switch having access to said lines, a directly operable magnet for controlling said switch to extend a connection to a particular group of lines, a relay in said switch adapted to prevent connection with all but the last line of a group of busy lines, another relay operable in series with said magnet for preventing the establishment of a connection to said last line, for stopping the operation of said magnet and for giving a busy signal to the calling subscriber when the called line is busy. 75
17. A connector including a relay, line switching contacts on said relay, an energizing circuit and a locking circuit for said relay, and holding means to retain said relay in operated position after the establishment of said energizing circuit and until said locking circuit is completed. 80
18. In a telephone system, an automatic switch having a primary movement and a variable directly controlled secondary movement in a different direction, a relay, a wiper of said switch being connected to one pole of a source of current by way of said relay while the switch is in normal position, contacts arranged in groups accessible to said wiper, one of said contacts being connected to the other pole of said source of current, means for operating said switch in its primary movement to associate said wiper with a particular group of contacts, and means for operating said switch in its secondary movement to close a circuit for said relay by bringing said wiper into engagement with the contact which is connected with said other pole of said source of current. 85
19. In a telephone system, an automatic switch having a primary movement and a directly controlled secondary movement, a relay, a wiper of said switch being connected to one pole of a source of current by way of said relay while the switch is in normal position, contacts arranged in horizontal levels accessible to said wiper, one of said contacts being connected to the other pole of said source of current, means for operating said switch in its primary movement to associate said wiper with a particular group of contacts, means for operating said switch in its secondary movement to close a circuit for said relay by bringing said wiper into engagement with the contact which is connected with said other pole of said source of current, means for preventing the operation of said relay during the secondary movement of the switch. 90
20. In a telephone system, an automatic switch having primary and secondary movements, said switch having a wiper and a plurality of groups of contacts accessible thereto, one or more of said contacts being connected with one pole of a source of current, a relay, means for seizing said switch, means responsive thereto for connecting the wiper with the other pole of said source of current by way of said relay, means for operating said switch in its primary movement to associate said wiper with a particular group of contacts, and directly controlled means for operating said switch in its secondary movement to close a circuit for said relay by bringing said wiper into engagement with a contact in the selected group. 95
21. In a telephone system, an automatic switch having primary and secondary movements, said switch having a wiper and a plurality of groups of contacts accessible thereto, one or more of said contacts being connected with one pole of a source of current, a relay, means for seizing said switch, means responsive thereto for connecting the wiper with the other pole of said source of current by way of said relay, means for operating said switch in its primary movement to associate said wiper with a particular group of contacts, directly controlled means for operating said switch in its secondary movement to close a circuit for said relay by bringing said wiper into engagement with a contact in the selected group, and means for disconnecting said wiper from the second named pole of said source of current during the secondary movement of the switch. 100
22. In a telephone system, an automatic switch having primary and secondary movements, said switch having a wiper and a plurality of groups of contacts accessible thereto, one or more of said contacts being connected with one pole of a source of current, a relay, means for seizing said switch, means responsive thereto for connecting the wiper with the other pole of said source of current by way of said relay, means for operating said switch in its primary movement to associate said wiper with a particular group of contacts, directly controlled means for operating said switch in its secondary movement to close a circuit for said relay by bringing said wiper into engagement with a contact in the selected group, and means for preventing the operation of said relay during the secondary movement of the switch. 105
23. In a telephone system, a connector switch having a wiper, a relay associated therewith, a called line having a bridge cut- 110

- 125
- 130

off relay, a contact connected with the last named relay accessible to said wiper, a circuit for applying ringing current to the called line, normally open contacts in said circuit controlled by the first named relay, means for associating said ringing circuit with the called line and for bringing said wiper into engagement with the first named contact to close a circuit including both of 10 said relays and said wiper in series.

24. In a telephone system, a connector switch having normally disconnected line wipers and a test wiper, a called line accessible to said line wipers, a test contact for 15 said called line accessible to said test wiper, said test contact being connected with one pole of a source of current, a relay for connecting said line wipers to the switch, means for bringing said line wipers into engagement with the called line and said test wiper into engagement with said test contact, means for connecting said line wipers with the switch by energizing said relay over a circuit including said test contact and said 20 test wiper in series, and means for shunting said wiper so as to place a guarding potential on said test contact.

25. In a telephone system, a connector switch having normally disconnected line 30 wipers and a test wiper a called line accessible to said line wipers, a test contact for said called line accessible to said test wiper, said test contact being connected with one pole of a source of current, a relay for connecting said line wipers to the switch, means for bringing said line wipers into engagement with the called line and said test wiper into engagement with said test contact, means for connecting said line wipers with the switch by energizing said 35 relay over a circuit including said test contact and said test wiper in series, means for shunting said relay so as to place a guarding potential on said test contact, and means for maintaining said relay energized after it is shunted.

26. In a telephone system, a connector switch having normally disconnected line wipers and a test wiper, a called line accessible to said line wipers, a test contact for 40 said called line accessible to said test wiper, said test contact being connected with one pole of a source of current, a relay for connecting said line wipers to the switch, means for bringing said line wipers into engagement with the called line and said test wiper into engagement with said test contact, means for connecting said line wipers with the switch by energizing said relay over a circuit including said test contact and said test wiper in series, means for shunting said relay so as to place a guarding potential on 45 said test contact, and means including a separate winding on said relay for maintaining it energized after it is shunted.

27. In a telephone system, a connector switch having normally disconnected line wipers and a test wiper, a called line accessible to said line wipers, a test contact for said called line accessible to said test wiper, 70 said test contact being connected with one pole of a source of current, a relay for connecting said line wipers to the switch, means for bringing said line wipers into engagement with the called line and said test wiper 75 into engagement with said test contact, means for connecting said line wipers with the switch by energizing said relay over a circuit including said test contact and said test wiper in series, means for shunting said relay so as to place a guarding potential on said test contact, and means for closing another circuit for said relay including a second winding thereon to maintain it energized after it is shunted. 80

28. In a telephone system, a connector switch including two talking conductors and two line wipers, a called line, means for operating said switch to cause said wipers to connect with the two conductors of said line, 90 a switching relay in said connector, contacts on said relay for connecting said talking conductors with said wipers, a third wiper on said connector, a cut-off relay for the called line, and a circuit including said third wiper for energizing said switching relay in series with said cut-off relay. 95

29. In a telephone system, a connector switch including two talking conductors and two line wipers, a called line, means for operating said switch to cause said wipers to connect with the two conductors of said line, 100 a switching relay in said connector for connecting said talking conductors with said wipers, a cut-off relay for the called line, a circuit for energizing said switching relay in series with said cut-off relay, contacts on said switching relay for closing a new circuit for the cut-off relay alone, and a locking circuit for said switching relay. 105

30. In a telephone system, a connector switch including two talking conductors and two line wipers, a called line, means for operating said switch to cause said wipers to connect with the two conductors of said line, 110 a switching relay in said connector, contacts on said relay for connecting said talking conductors with said wipers, a cut-off relay for the called line, a circuit for energizing said switching relay in series with said cut-off relay, and means actuated automatically during the operation of said connector for holding said circuit open until after the said wipers have completed the connection to the called line. 115

31. In a telephone system, a connector switch, means for operating said connector to connect with a called line, a switching relay for closing the talking connection, a test relay for preventing the closing of such con- 120

- nection if the called line is busy, a slow acting relay maintained energized while the switch is operating, and a circuit for said switching relay controlled jointly by said test relay and slow acting relay. 5
32. In a telephone system, a connector switch, means for operating said connector to connect with a called line, a switching relay for closing the talking connection, a test relay for preventing the closing of such connection if the called line is busy, a slow acting relay maintained energized while the switch is operating, a circuit for said test relay controlled by said slow acting relay, and a circuit for said switching relay controlled jointly by said test relay and slow acting relay. 10
33. In a telephone system, a connector switch, means for operating said connector to connect with a called line, a switching relay for closing the talking connection, a test relay for preventing the closing of such connection if the called line is busy, a slow acting relay maintained energized while the switch is operating, a circuit for said test relay controlled jointly by said slow acting relay and said switching relay, and a circuit for said switching relay controlled jointly by said test relay and slow acting relay. 15
34. In a telephone system, a connector switch including a talking conductor and a line wiper, a called line, means for operating said switch to cause said wiper to connect with a conductor of said line, a switching relay in said connector for connecting said talking conductor with said wiper, a cut-off relay for the called line, a circuit for energizing said switching relay in series with said cut-off relay, contacts on said switching relay for closing a new circuit for the cut-off relay alone, and a locking circuit for said switching relay. 20
35. In a telephone system, a trunk line terminating in an automatic switch, groups of lines accessible to said switch, means for seizing said trunk line and for operating said switch to select one of said groups of lines, means for initiating an automatic secondary movement of said switch to select any idle line in the selected group of lines, a relay energized when an idle line is found for completing a connection to said idle line, a circuit for the winding of said relay including a conductor of said trunk line, and means for closing said circuit to operate said relay. 25
36. In a telephone system, a connector switch including a talking conductor and a line wiper, a called line, means for operating said switch to cause said wiper to connect with a conductor of said line, a switching relay in said connector for connecting said talking conductor with said wiper, a cut-off relay for the called line, a circuit excluding said wiper for energizing said switching relay in series with said cut-off relay, contacts on said switching relay for closing a new circuit for the cut-off relay alone, and a locking circuit for said switching relay. 30
37. In a telephone system, a side switchless connector having two directive motions, for selecting a called line, a two conductor talking circuit extending through said connector to the wipers thereof and comprising three normally disconnected sections, a ringing generator normally operatively associated with the middle section, a cut-off relay for the called line, a switching relay in said connector energized in series with said cut-off relay when the called line is selected, contacts on said relay for joining the middle and last sections to ring the called line, a ring cut-off relay energizing over said two connected sections on the response of the called party, and contacts on said ring cut-off relay for disassociating said middle section and the said ringing machine and for connecting the middle section with the first section to complete the talking circuit through said connector. 35
- Signed by me at Chicago, Cook County, State of Illinois, this 6th day of June, 1917.

EMIL JACOBSEN.
